FURNITURE SHOE

Application filed November 28, 1930. Serial No. 498,560.

The objects of the present invention are to provide a cushioned shoe for furniture, which will be of simple, inexpensive, easily applied design, which will not scratch or mar the floor and one in which the cushion material will hold its shape without unduly spreading, bulging or fraying and will remain effective even with long wear and hard usage.

These objects are attained by a novel form 10 of cushion and a novel construction of mounting for the same, the details of which will appear as the specification proceeds.

The drawings accompanying and forming part of the specification illustrate one practical embodiment of the invention.

In the several views shown, Fig. 1 is a broken side elevation partly in section showing a form of the invention applied to the leg of an article of furniture, such as a chair or table; Fig. 2 is a bottom plan view of the shoe; Fig. 3 is a top plan view of the same; Fig. 4 is a detail of the cushion material.

In Fig. 1, the leg of a chair or other piece of furniture is indicated at 5 and the body of 25 the shoe is indicated at 6 in the form of a die casting having a tapered socket 7 in the top of the same to fit the furniture leg, a parallel sided socket 8 in the bottom of the same to receive the cushion material and a transverse 30 intermediate partition 9 separating the two sockets.

The transverse intermediate partition forms a backing for the cushion material and serves also in the present instance, as a mounting for anchoring spikes or prongs 10 adapted to be driven up into the foot of the furniture leg. In the central portion, the partition is shown as having an opening 11 through which a nail or other fastening 12 may be 40 driven up through the crating 13 of the furniture into the end of the furniture leg.

The cushion material is of special form 45 consisting of a strip or strips of fabric 14 creased and folded upon itself in shallow V-shaped plaits 15, the plaited strip being rolled in the form of a generally solid plug as indicated in Fig. 4 and forced through a suitable die as in patent application Ser. 419, 014 into seated relation in the socket 8.

50 After plaiting or in the course of plait-

ing, the strip may be "rubberized" or be given a backing of adhesive or rubberized material, which as indicated at 16 in Fig. 4, holds the plaits in folded relation and also to an extent water-proofs the material, protecting the finished product from mop water, vermin, etc.

This rubberized backing also has a tendency as the material is compressed in the die to hold it compressed in the shape given it by the die.

The main advantage attained by the plaiting is that the material does not ravel and fray out where it is exposed at the foot of the shoe, because there are no flat extended exposed surfaces of material, the only portions exposed being ridges or narrow plaits of the material and only the edges of these are exposed to the outside. Consequently, the cushion can not flatten out or spread. 70 These plaits act as longitudinal reinforcements of the plug material, which while preventing spreading, do not take away from the longitudinal elasticity of the plug. All 75 four of the exposed edges of the plug are equally resistant to wear, so the furniture may be pushed about in various directions, without causing the cushioning plug to spread, or ravel, or sag, one way or the other.

The body or base of the shoe may be made 80 as a single die casting with the anchoring prong or prongs molded as integral parts of the intermediate partition. These prongs are sufficient ordinarily for securely fastening the shoe on the furniture leg. In the 85 case of wooden furniture, the prongs may be driven directly into the lower end of the furniture leg. In the case of steel furniture, wooden plugs are usually driven into the hollow metal legs and the prongs then driven 90 into these wooden plugs. These furniture shoes may be applied at any time and when 95 in place do not interfere with the crating and packing operations, it being seen in Fig. 1 that the nails for fastening the crating may be driven straight up through the cushion material and through the openings in the shoe partitions into the legs or supports of the furniture.

The rolled plugs of plaited cushion strip 100

are compressed sufficiently for them to hold in place in their sockets, but if desired, adhesive or other fastening medium may be additionally employed.

5 While in Fig. 4 the fabric is shown as coiled with the adhesive layer 16 on the inside, it will be apparent that the strip may be coiled with the adhesive backing on the outside where it will form in effect a waterproof "facing" more completely protecting the plaited material from mop water and vermin. Other changes and modifications may be made all within the scope of the claims.

What is claimed is:

15 1. A furniture shoe cushion, comprising a fabric strip plaited in small folds and closely rolled in the form of a plug with the end edges of the plaits exposed at the ends of the plug.

20 2. A shoe cushion for furniture and the like, comprising a plaited strip of fabric having a backing for holding the folds of the plaits in the plaited condition and said backed plaited strip being compacted into a plug 25 with the ends of the plaits exposed at the ends of the plug.

30 3. A furniture shoe, comprising a rigid hollow tubular shell open at both ends and having intermediate the ends of the same an internal transverse partition separating the interior of the tubular shell into sockets which are open to the opposite ends of the shell, a cushion of fabric layers arranged on edge and compressed into a block, said block 35 being seated in the open socket in one end of the shell with the edgewise disposed fabric layers at the inner end of the plug bearing against the transverse partition for support and the opposite or exposed face of the plug being flat to bring the edges of the layers of 40 fabric into position for equal supporting engagement with a floor surface, whereby said cushion plug has a wide supporting area substantially equal to the full cross sectional dimensions of the shell, said edgewise disposed fabric plug being confined and held in said 45 socket against spreading and against separation from the shell whereby the shoe as a single complete unit may be applied by simple engagement of the socket in the opposite end of the shell over the end of the leg of an article of furniture and will thereupon provide a flat support substantially as wide in supporting area as the full end of the furniture 50 leg.

55 4. A furniture shoe, comprising a rigid hollow tubular shell open at both ends and having intermediate the ends of the same an internal transverse partition separating the interior of the tubular shell into sockets which are open to the opposite ends of the shell, a cushion of fabric layers arranged on edge and compressed into a block, said block being seated in the open socket in one end of the shell with the edgewise disposed fabric lay-

ers at the inner end of the plug bearing against the transverse partition for support and the opposite or exposed face of the plug being flat to bring the edges of the layers of fabric into position for equal supporting engagement with a floor surface, whereby said cushion plug has a wide supporting area substantially equal to the full cross sectional dimensions of the shell, said edgewise disposed fabric plug being confined and held in said 70 socket against spreading and against separation from the shell whereby the shoe as a single complete unit may be applied by simple engagement of the socket in the opposite end of the shell over the end of the leg of an article of furniture and will thereupon provide a flat support substantially as wide in supporting area as the full end of the furniture leg and the fabric layers being folded relative to each other and arranged with such folds extending longitudinally of the plug and exposed at the sides of the plug to prevent fraying and undesirable spreading of the plug and to provide a multitude of folded-edge fabric supports at the exposed side portions 80 of the plug.

In testimony whereof we affix our signatures.

FRED JANTZEN.

JOSEPH J. LYNCH.
